UNITED STATES PATENT OFFICE.

JOHN S. HOPKINS, OF BROOKLYN, NEW YORK, ASSIGNOR OF TWO-FIFTHS TO LEWIS G. ANDREWS, OF BROOKLYN, NEW YORK.

HEAT-INSULATED RECEPTACLE.

1,000,172.

Specification of Letters Patent. Patented Aug. 8, 1911.

Application filed August 20, 1910. Serial No. 578,241.

To all whom it may concern:

Be it known that I, JOHN S. HOPKINS, a citizen of the United States, residing at Brooklyn, in the county of Kings and State 5 of New York, have invented certain new and useful Improvements in Heat-Insulated Receptacles; and I do hereby declare the following to be a full, clear, and exact description of the invention, such as will enable others skilled in the art to which it 10 pertains to make and use the same.

This invention relates to certain new and useful improvements in receptacles of that general class adapted to maintain a certain 15 temperature for practically an indefinite period.

It has for its objects among others to provide an improved receptacle which shall be simple, yet possessing great durability and 20 which will prevent excessive vertical vibration and thus protect the jointures between the inner and outer vessels. The receptacles are preferably constructed entirely of metal, thus being exceedingly durable and possessing 25 great stability, rendering them, in a sense, practically indestructible.

I aim also at improvements in the cap which enhances the durability and desirability of the receptacle, said cap being 30 placed over the completed vessel and the outer and inner edges crimped inwardly to fit tightly to the retainer.

Other objects and advantages of the invention will hereinafter appear and the 35 novel features thereof will be particularly pointed out in the appended claims.

The invention is clearly illustrated in the accompanying drawings, which, with the 40 numerals of reference marked thereon, form a part of this specification, and in which—

Figure 1 is a substantially central vertical section through the receptacle. Fig. 2 is a similar view showing the receptacle with an outer jacket and an outer cap or cup. Fig. 45 3 is a similar view through the oval receptacle with the cap and bottom plug removed. Fig. 4 is a section similar to Fig. 2 of the receptacle shown in Fig. 3 provided with an outer jacket and the outer cap or 50 cup in position. Fig. 5 is a horizontal section on the line 5—5 of Fig. 2. Fig. 6 is a horizontal section on the line 6—6 of Fig. 4. Fig. 7 is an enlarged detail of the turned seam at the junction of the bottom of the 55 outer vessel. Fig. 8 is an enlarged detail of

the non-heat conducting pad showing the recess therein for the reception of the inner vessel.

Like numerals of reference indicate like parts throughout the several views.

The receptacles may be manufactured in the form of refrigerators, flasks, pots, bottles, iceboxes, pans, siphons, tanks, coolers, refrigerating cars, grips, satchels, carrying-cases and any and all other forms or shapes 60 or sizes, according to the purpose for which said receptacles may be desired or by or through which it is desired to retain liquids or other substances or space at a desired temperature for an indefinite period of time. 70

In the present instance I have shown receptacles of substantially cylindrical and oval form, merely as examples of some ways in which the invention may be utilized. The cylindrical receptacles I preferably construct of plain or smooth surfaced sheet metals, while flat or oval receptacles are 75 preferably constructed in part of corrugated sheet metals in the form of a double walled vessel embodying a vacuum. 80

In the course of construction of the receptacles, the metals are, by preference, coated with an agate or enameling solution, to make the metal impervious, although it is evident that the essentials of the invention 85 are not affected by the rendering of the materials impervious.

Referring to the drawings, in carrying out the invention, the preferable mode of procedure is as follows. Referring first to 90 Figs. 1, 2 and 3, I take an inner vessel 1 of sheet metal, copper, brass, zinc or other pliable metallic material, made substantially cylindrical in form and somewhat restricted at the neck, as seen at 2, 3 being the neck. 95 The outer vessel 4 is cylindrical in form, conforming in its general shape to that of the inner vessel 1, restricted at the neck, as at 5, 6 being the neck. These two vessels are suitably joined or united at the top, as 100 seen at 7, by seaming, brazing, soldering, welding or otherwise, the outer vessel being constructed of sheet metal, such as copper, brass, zinc or the like.

8 is the bottom of the inner vessel secured 105 thereto in any suitable manner, as by suitable seam, as seen at 9. 10 is a supplemental bottom designed to prevent excessive or extreme vibration of the inner vessel 1. 11 is the bottom of the outer vessel or receptacle, 110

to which the sides or walls of said outer vessel are secured in any suitable manner, as for instance by a turned seam, as seen at 12 in Fig. 1, and in the enlarged detail 5 Fig. 7. Between these two bottoms 8 and 11 is placed a suitable heat non-conducting substance 13 which also serves to assist in arresting the vertical vibration.

Between the inner and outer vessels is a 10 space 14 and between the inner and outer bottoms is a smaller space 15, from which spaces the air is designed to be expelled, so as to create a vacuum. This may be accomplished in any suitable manner. In the 15 present instance, I have shown the outer bottom 11 as provided with a suitable aperture 16 which is internally threaded, as at 17, for the reception of a suitable plug 18 which, when secured in place, forms an air-tight seal. This plug is shown as tapered but, of course, this is not essential. The 20 plug is provided with a slot 19 in its outer end for the reception of a screw driver or other implement by which it may be removed or screwed tightly into place.

20 is a wire secured to the bottom of the inner vessel and preferably retained in the seam or jointure of the walls or sides and bottom thereof. This wire is seen best 30 in Fig. 5. It is designed to rest in notches or seats 21 in the stays 22 which are supported on the supplemental bottom 10, being preferably formed integral with said bottom by being stamped or cut therefrom and 35 turned up at right angles so as to form the said stays or supports. The wire 20 rests within these notches in these stays, as seen in Figs. 1 to 6.

23 is the cap for use on the vessels or receptacles without the outer covering or jacket. It extends over the jointure between the inner and outer vessels at the top and is internally threaded, as seen at 24, to receive the screw-threaded stopper or plug 25, 45 26 being a gasket of any suitable material, such as pressed paper, india rubber, cork or any other pliable material placed around the upper end of the plug or stopper 25 beneath the peripheral edge 27 thereof, to 50 prevent leakage at the mouth or neck of the bottle or retainer. This cap is provided with the depending skirt or flange 28 between which and the neck of the outer vessel there is a space 29 designed to be filled 55 with a plastic composition suitable for binding the cap to the top and around the neck of the structure.

30 is an indentation which may extend entirely around the neck of the outer vessel 60 or for a portion only of the same, which is designed to be filled with a suitable plastic composition, so as to secure the skirt of the cap to the neck of the outer vessel and this aids also in strengthening the structure. At 65 31 the lower edge of the skirt is turned or

crimped in toward the neck of the outer vessel, so as to fit tightly thereto.

The oval or flat vessels or receptacles are substantially identical with those just described except as to shape, as will be clearly 70 understood upon reference to Figs. 3, 4 and 6.

The vessels hereinbefore described may sometimes be provided with an outer covering or jacket, shown at 32, constructed to 75 conform to the general shape of the vessels being, of course, of greater dimensions and constructed of any desirable suitable material. Between this outer jacket and the outer vessel 4 is a space 33 which is designed 80 to be filled with suitable plastic or non-conducting material or composition, so as to bind the outer jacket and the outer vessel 4 together. I sometimes propose to make the outer jacket or covering of a suitable 85 non-metallic material, in which instance this space 33 may be omitted, or it may be present and the non-conductive material 34 omitted.

Referring to Fig. 2, there will be seen a 90 tri-equidistant indentation 35 at the neck of the outer jacket or covering 32 for the purpose of holding in place when adjusted the outer cap or cup 36. This indentation is disposed below the indentation in the neck 95 of the outer vessel 4, as seen in Fig. 2, and the outer cup or cap serves to strengthen and reinforce the structure at this point. This cap serves also as a protection or guard for the inner stopper, and when removed 100 may be used as a drinking cup. The top edge of the said cup or cap, that is what constitutes the top edge when used as a drinking vessel, is preferably beaded, as shown at 37, by means of a wire in the usual 105 manner. 38 is a flange extending inward at the upper end of the outer covering or jacket 32, which when fitted in place rests snugly on the bonding joint or jointure of the two vessels 1 and 4 at the upper end of 110 the neck.

In some instances I may employ in lieu of the screw-threaded cap or plug 25, an ordinary stopper 39, as seen in Figs. 2 and 4.

From the above, it will be seen that I have 115 devised a simple and efficient durable receptacle capable of manufacture at nominal cost and which in use will be found serviceable, possessing stability and not liable to breakage or injury in use or transportation; and while the structural embodiment of the invention as hereinbefore disclosed is what I at the present time consider preferable, it is obvious that the same is 120 subject to changes, modifications and variations in the details, shape, proportion of parts etc. I, therefore, do not intend to restrict myself to the particular construction herein disclosed, but reserve the right to make such changes, variations and modifi- 125 130

cations as come properly within the scope of the protection prayed.

What is claimed as new is:—

1. A heat insulated receptacle comprising 5 inner and outer vessels, a supplemental bottom on the bottom of the outer vessel, stays integral with the supplemental bottom and rising therefrom, the stays having notches in which the bottom of the inner vessel is 10 received, and a wire retained in the joint at the bottom of the inner vessel and engaged in said notches.

2. A heat insulated receptacle comprising 15 inner and outer vessels, a supplemental bottom on the bottom of the outer vessel, stays integral with the supplemental bottom for supporting the inner vessel, a cap secured to the neck of the outer vessel with an interposed plastic composition and en- 20 gaging the top edge of the inner vessel, and a stopper for the inner vessel.

3. A heat insulated receptacle comprising 25 inner and outer vessels, a supplemental bottom on the bottom of the outer vessel, stays integral with the supplemental bottom for supporting the inner vessel, the neck of the outer vessel having a circumferential indentation, a cap extending below said indentation and secured to the 30 neck of the outer vessel with an interposed plastic composition, and a stopper for the inner vessel.

4. A heat insulated receptacle comprising 35 inner and outer vessels, a supplemental bottom on the bottom of the outer vessel, stays integral with the supplemental bottom for supporting the inner vessel, the neck of the outer vessel having a circumferential indentation, a cap extending below said indentation and secured to the 40 neck of the outer vessel with an interposed plastic composition, the cap having an inner downwardly extending flange, and a stopper fitting into said flange for closing the inner vessel.

45 5. A heat insulated receptacle comprising inner and outer vessels, a supplemental

bottom on the bottom of the outer vessel, stays integral with the supplemental bottom for supporting the inner vessel, the neck of the outer vessel having a circum- 50 ferential indentation, a cap extending below said indentation and secured to the neck of the outer vessel with an interposed plastic composition, the cap having an inner downwardly extending flange, a stopper 55 fitting into said flange for closing the inner vessel, a jacket inclosing the outer vessel and having a circumferential groove in its neck, and a drinking cup provided with a bead adapted to fit into said groove, where- 60 by the cup is removably attached to the neck of the jacket.

6. A heat insulated receptacle comprising 65 inner and outer vessels, a supplemental bottom below the bottom of the inner vessel, a non-conducting material interposed between the supplemental bottom and the bottom of the outer vessel, stays integral with the supplemental bottom and rising therefrom, the stays having notches in which the 70 bottom of inner vessel is received, a wire retained in the joint at the bottom of the inner vessel and engaged in said notches, the neck of the outer vessel having a circumferential indentation, a cap extending 75 below said indentation and secured to the neck of the outer vessel with an interposed plastic composition, the cap having an inner downwardly extending flange, a stopper fitting into said flange for closing the inner 80 vessel, a jacket inclosing the outer vessel and having a circumferential groove in its neck, and a drinking cup provided with a bead adapted to fit into said groove; where- 85 by the cup is removably attached to the neck of the jacket.

In testimony whereof I affix my signature in presence of two witnesses.
